UNITED STATES PATENT OFFICE.

JACOB W. FIELD, OF PEORIA, ILLINOIS.

GAME DEVICE.

Application filed September 24, 1926, Serial No. 137,488. Renewed February 3, 1928.

This invention pertains to game devices. More specifically it relates to improvements in dice boxes.

An object of the invention is to provide a dice box of two parts suitably connected and each having one or more pockets or recesses to register with one another wherein to enclose the dice for change in reading position.

Another object is to provide a dice box of two parts hingedly connected to close upon one another, one of the parts having a pocket or recess but little larger in diameter than the die it is to receive the other part having a registering pocket or recess of larger diameter than the first wherein the die may be made to readily change its position and then returned to the smaller pocket or recess for reading.

Still another object is to provide a dice box of two hingedly related parts each having a pocket or recess in register with one another but of unequal diameter whereby to provide a shoulder or ledge in the path of movement of the die to be contained in said recess to aid in the change of position of said die as and when the box is inverted in position.

In the appended drawing forming part hereof

Figure 1 is a plan of the invention showing two hingedly connected parts shown in their separated positions.

Figure 2 is a sectional elevation of the same in the open or separated position as seen on line 2-2, Figure 1, and

Figure 3 is a sectional elevation of the device taken on the same line as Figure 2, the two parts being shown closed upon one another or in the position for use.

The device consists of two parts, a lower one 1 and an upper one 2, the two being connected by a hinge member 3 so as to fold one upon the other as in Figure 3. While the said parts 1 and 2 may be of any preferred form of outline, each in this instance is cylindrical in shape with flattened ends and may be made of wood, bakelite, or other material, preferably light in weight, and having faces 4 adapted to abut as shown in said Figure 3.

The lower part 1 is furnished with one or more pockets or recesses 5 below the face 4 each of which is sufficiently large to receive and hold a die and of a depth about equal to

its diameter, this, however, being mere choice.

The upper part 2 is likewise provided with one or more pockets or recesses 6 corresponding in position to the pockets or recesses 5. Said pockets 6 are preferably much deeper and somewhat greater in diameter than the pockets 5 so that when the said parts are closed upon one another said pockets or recesses present the appearance shown in Figure 3. That is to say, since the pockets 6 are greater in diameter than the pockets 5 a ledge 7 is exposed on the surface 4 of the part 1, this being indicated both in Figures 1 and 3.

Contrary to the manner of use of the ordinary open end dice box whose use requires the dice to be strewn upon a table-top to be read, in my device the dice are retained by closing the parts upon one another and inverting it so that said dice in falling from the smaller pockets 5 into the larger ones 6 are free to alter their positions within the latter and when returned to said pockets 5 may be read, upon opening the parts, the surfaces of the dice preferably lying substantially flush with the surface 4 of the lower part 5 where they may be easily read.

Not only can the dice alter their positions by moving about within the larger pockets 6 but as they fall from said pockets back into the pockets 5 they will lodge momentarily upon the narrow ledges 7, see Figure 3, and compelled to change position and must always present a different reading face 5 to the player upon reaching said pocket 5.

In lieu of spreading the dice by throwing them from an open box it is clear that it is only required in the use of my box that mere inversions of the box be made and the opening and closing of the parts thereof and without danger of loss of any of the dice.

While I have shown and described a preferred form of my invention I may alter its form in any desired way or provide the equivalent of the construction shown without departing from the spirit of the invention while keeping within the scope of the appended claims.

I claim:

1. A box for the game of dice consisting of two bodies adapted to lie upon one another, one of the bodies having a series of shallow pockets exposed at the meeting place of the bodies, each of a diameter but

105

110

- slightly in excess of that of a die, the other of the bodies also having a series of pockets greater in diameter and of greater depth than the first named pockets and exposed to the latter and so disposed with respect to the same when the bodies overlie one another as to expose an annular abutment on the first body at each of said first named pockets.
10. 2. A box for use in the game of dice including two bodies adapted to abut upon one another, one of them having a series of pockets each of a depth and diameter slightly greater than the greatest diameter of a die, the same being exposed to the other of the bodies, said other body also having a series of larger pockets exposed to the first said pockets and disposed with respect to the latter as to expose on the first named body an annular abutment at each first pocket with which the dice engage in passing from one body into the other.
15. 3. A box for use in the game of dice including two bodies adapted to abut upon one another, one of them having a series of pockets each of a depth and diameter slightly greater than the greatest diameter of a die, the same being exposed to the other of the bodies, said other body also having a series of larger pockets exposed to the first said pockets and disposed with respect to the latter as to expose on the first named body an annular abutment at each first pocket with which the dice engage in passing from one body into the other, and means for holding the bodies in abutment.
20. 4. A box for use in the game of dice including two bodies adapted to abut upon one another, each having a series of pockets in its abutting side, the two series being ex- posed to one another, each pocket of one of the series being of a depth and diameter slightly greater than the greatest diameter of a die, each pocket of the other series being of a larger diameter than those of the first described series whereby to permit the dice therein to readily alter their positions, the axes of the pockets of the two series being in alignment, there being an abutment between the two series of pockets with which the dice are adapted to have contact in their passage from the larger to the smaller pockets.
25. 5. In a device for the purpose described, a pair of parts each having a face adapted to lie one upon the other and each having a pocket or recess therein opening upon the face thereof, the pockets or recesses adapted to register with one another, means included in the structure between the pockets or recesses lying in the path of a die enclosed in the pockets or recesses as it shifts from one to the other of the latter, and means to secure the parts in a given position when abutting one on the other.
30. 6. In a device for the purpose described, a pair of parts each having a face adapted to lie one upon the other and each having a pocket or recess therein opening upon the face thereof, the pockets or recesses adapted to register with one another and one having greater diameter than the other, means included in the structure between the pockets or recesses lying in the path of a die enclosed in the pockets or recesses as it shifts from one to the other of the latter, and means to secure the parts in a given position when abutting one on the other.

In testimony whereof I affix my signature.
JACOB W. FIELD.
